[57] CLAIM

The ornamental design for a chest pouch, as shown and described.

DESCRIPTION

FIG. 1 is a front elevational view of a chest pouch showing my new design;

FIG. 2 is a back elevational view thereof;

FIG. 3 is a side elevational view thereof, taken from the right side shown in FIG. 2;

FIG. 4 is an opposite side elevational view thereof;

FIG. 5 is a top plan view of my design as shown in FIG. 2;

FIG. 6 is a bottom plan view thereof; and,

FIG. 7 is a top plan view thereof, showing the pouch portion open.
